REFINING ENGINE FOR USE IN PULP
REFININGWilliam Groundwater Fraser, Fulham, London,
EnglandApplication March 5, 1931, Serial No. 520,450,
and in Great Britain February 10, 1931

7 Claims. (Cl. 92—27)

This invention relates to refining engines of the conical type used in the manufacture of paper and in allied industries and the object of the invention is to provide an improved and simplified arrangement employing more than one conical refining element on a common operating shaft.

According to the present invention an improvement is provided wherein two co-operating conical refining units are so disposed that the stuff passes directly from one unit to the other without the use of external connections whilst means are provided for adjusting the outer cones relatively the one to the other or simultaneously for the purposes of imparting extra pressure when required or for taking up wear.

Reference will now be made to the accompanying drawings which illustrate by way of example constructions according to the invention and in which:

20 Fig. 1 is an elevation partly in section of one form of refining engine,

Fig. 2 is an end elevation,

Fig. 3 is a plan with the upper halves of the outer shells removed,

25 Fig. 4 is a detail view of the adjusting mechanism for one of the cones and

Fig. 5 is an elevation partly in section showing a modified arrangement.

In the construction illustrated in Figs. 1—4 two conical refining elements are disposed around a common central shaft 1, these elements including rotors 2 and 3 fixed to the said shaft to rotate therewith and relatively fixed outer casings or shells which intercommunicate and are formed with removable upper sections 4 and 5 and lower sections 6 and 7. The lower halves 6 and 7 of the two casings are formed with downwardly extending portions 8 which engage guide members 9 formed above a sole plate 10 and constructed to permit longitudinal movement of the outer shells relatively to the shaft 1 as hereinafter described.

The shaft 1 is carried at its ends in water cooled thrust bearings 11 and one end is connected through a flexible coupling 12 with an electric motor 13 which is also bolted to the sole plate 10 or to an extension thereof.

45 The two rotors 2 and 3 are hollow as shown in Fig. 1 and are both tapered in the same direction the larger end of the rotor 2 having an annular socket 14 into which a spigot 15 on the smaller end of the rotor 3 engages. The two rotors are held in this position of engagement by rods 16 and nuts 17 disposed in recesses 18 formed in the outer ends of the two rotors. The exteriors of

the two rotors are formed or provided with blades or bars 19 which co-operate in known manner with similar bars 20 formed on the interiors of the outer shells.

The larger end of the rotor 2 is curved as shown 60 at 21 in Fig. 1 so as to form around it an annular passage at the point of connection between the two outer shells. At this point the smaller end of the shell 5—7 is outwardly flared to form a flange 21a whose external diameter is equivalent 65 to the external diameter of the shell 4—6 at its larger end. To form a closed annular chamber 22 at this point the two shells are connected by a coupling 23 of flexible material such as india rubber which is fixed onto the shells with a wire 70 winding 24 and is initially curved as shown so as to permit one of the shells to be adjusted relatively to the other. The inlet to the refiner is at 25, the stuff passing between the shell 4—6 and rotor 2 to the annular chamber 22 from which 75 it passes between the shell 5—7 and rotor 3 to an outlet 26 which opens from an annular chamber 27 formed around the larger end of the rotor 3.

80 Mounted in bearings in the sole plate is a screw threaded spindle 28 which is utilized for the purpose of effecting adjustments in the positions of the shells 4—6 and 5—7. Adjustment is normally effected by means of a hand wheel 29 mounted on a shaft whose inner end carries a 85 worm engaging a worm wheel 30 fixed on the spindle 28. The spindle is so mounted as to be capable of rotary but not longitudinal movement so that its rotations impart longitudinal movement to a bracket 31 carrying a boss 32 which 90 engages with a slot in the under side of the shell 4—6. The spindle 28 is associated with a second bracket 33 also having a boss 34 which engages with a slot at the under side of the shell 95 5—7. By these means rotation of the hand wheel 29 in either direction causes simultaneous longitudinal movement in either direction of the two outer shells 4—6 and 5—7.

In order that it may be possible to adjust the shell 5—7 independently relatively to the shell 4—6 in cases where additional pressure is required at the second stage the bracket 33 is mounted over a sleeve 35 formed integral with a worm wheel 36 and internally screw threaded at 37 (as shown in Fig. 4) to engage the spindle 28. The worm wheel 36 is engaged by a worm on the inner end of a spindle 38 provided with a handle 39 movement of which causes the sleeve 35 to travel in either direction along the spindle 28 and consequently move the shell 5—7 without 110

disturbing the setting of the shell 4—6. When, however, the hand wheel 29 is operated the sleeve 35 is moved along the spindle 28 in the same manner as the bracket 31 and the two shells are 5 simultaneously adjusted both to the same degree.

The upper portions 4 and 5 of the shells are bolted to the lower portions 6 and 7 through co-operating sockets 40 cast on their sides, the 10 division of the shells longitudinally enabling the machine as a whole to be dismantled without the necessity for providing room to extract the central shaft 1 and rotors 2 and 3 endwise.

For cleaning purposes the annular chamber 22 15 is provided with outlets 41 normally closed by doors 42.

In the form of construction illustrated in Fig. 5 two co-operating conical refining elements are 20 assembled in the same relative position as in the construction previously described. In this case, however, the outer shell 42a of one unit is formed at its end of greater diameter with an annular flange 43 which overlaps a flange 44 of smaller diameter formed on the smaller end of 25 the outer shell 45 of the second refining unit. Within the flange 43 is formed an annular groove in which is seated a ring 46 of india rubber or other packing material arranged to bear upon the outer cylindrical surface of the flange 44, to 30 make a fluid tight joint therewith in all positions of adjustment of the two outer shells.

Said outer shells 42a and 45 are provided with 35 independent means of adjustment, that is to say, separate hand wheels 47 and 48 are provided 40 to operate screw threaded spindles 49 and 50 to move brackets 51 mounted on said spindles and having projections 52 which engage with recesses on the under side of adjacent members 53, a number of which members 53 extend downwardly 45 from the shells 42a and 45 and are slidable in guides 54 extending upwardly from the sole plate 55.

Both forms of the machine above described 45 are constructed so that they can be operated under much greater pressure of stuff supply than has hitherto been possible as with the present constructions the stuff can be pumped direct into the machine and the outlet controlled through a valve or other means, this serving to 50 raise the pressure in the interior of the refiner to a much greater extent than has hitherto been done. In addition to this the invention also possesses the advantage that the construction is simplified by avoiding the use of external connections between the two conical refining units 55 which are now brought so close together that the stuff passes directly from the one to the other.

I claim:

1. A machine for refining paper pulp comprising 60 two conical refining units comprising rotors and coacting shells, said rotors and shells tapering in the same direction, a shaft on which said rotors are coaxially mounted, said shells being in communication for feeding the material under treatment directly from one unit to the other, means for adjusting the said shells simultaneously, and means for adjusting the shell of one unit independently of the other unit.

70

2. A machine for refining paper pulp according to claim 1 having a connecting means between the shells permitting one shell to slide relatively to the other shell during adjustment.

3. A machine for refining paper pulp comprising 75 two conical refining units comprising rotors and coacting shells, said rotors and shells tapering in the same direction, a shaft on which said rotors are coaxially mounted, said shells being in communication for feeding the material under treatment directly from one unit to the other, means for adjusting the said shells simultaneously, means for adjusting the shell of one unit independently of the other unit, said rotors and shells coacting to form an annular chamber connecting the discharge end of one unit with the inlet end of the other unit, and a flexible wall about said chamber permitting relative adjustment of the shells.

4. A machine for refining paper pulp comprising 80 two conical refining units comprising rotors and coacting shells, said rotors and shells tapering in the same direction, a shaft on which said rotors are coaxially mounted, said shells being in communication for feeding the material under 85 treatment directly from one unit to the other, a screw shaft, means on the shell engaged by the shaft so that the shells may be adjusted simultaneously, an operating member and worm wheel for rotating said shaft, and means associated 90 with said screw shaft for adjusting the shell of one unit independently of the other unit.

5. A machine for refining paper pulp comprising 95 two conical refining units comprising rotors and coacting shells, said rotors and shells tapering in the same direction, a shaft on which said rotors are coaxially mounted, said shells being in communication for feeding the material under treatment directly from one unit to the other, a screw-threaded shaft by which the shells are adjusted simultaneously, an operating member and 100 gearing for rotating said shaft, means engaging the shells and engaged by said shaft including a boss having a bracket threaded to the shaft and 105 engaging one of the shells, gearing on said bracket, and an auxiliary device for operating the last mentioned gearing to effect independent adjustment of one shell relatively to the other shell.

6. A machine for refining paper pulp comprising 110 two conical refining units comprising rotors and coacting shells, said rotors and shells tapering in the same direction, a shaft on which said rotors are coaxially mounted, said shells being in communication for feeding the material under 115 treatment directly from one unit to the other, a screw shaft, brackets, a sleeve on which one of 120 said brackets is journaled, said sleeve and the other bracket being screw threaded to said shaft, means for rotating said shaft to effect simultaneous 125 adjustment of both shells, and an auxiliary 130 adjusting device operatively connected to said sleeve so that the latter may be moved to effect independent adjustment of one shell relatively to the other shell.

7. A machine for refining paper pulp according 135 to claim 6 having boss connections between the brackets, shells and gearing.
